(57)

CLAIM

The ornamental design for a hand dryer, as shown and
described.

DESCRIPTION

FIG. 1 is a top perspective view of a hand dryer, showing the
new design;

FIG. 2 is a bottom perspective view of the hand dryer;

FIG. 3 is a front elevational view of the hand dryer;

FIG. 4 is a rear elevational view of the hand dryer;

(Continued)

FIG. 5 is a left side elevational view of the hand dryer;
 FIG. 6 is a right side elevational view of the hand dryer;
 FIG. 7 is a top plan view of the hand dryer; and,
 FIG. 8 is a bottom plan view of the hand dryer.
 The broken lines shown in the drawings depict portions of
 the hand dryer that form no part of the claimed design.
